[57] **CLAIM**

The ornamental design for a galvanic biofeedback skin response device, as shown.

DESCRIPTION

FIG. 1 is a top plan view of a galvanic biofeedback skin device illustrating my novel design;

FIG. 2 is a bottom plan view of FIG. 1;

FIG. 3 is a side elevation of FIG. 1 looking at the near lower edge thereof;

FIG. 4 is a side elevational view looking at the side opposite that shown in FIG. 3;

FIG. 5 is an end elevational view looking from right to left at FIG. 1;

FIG. 6 is an end elevational view looking at the end opposite that shown in FIG. 5; and

FIG. 7 is a perspective view of the device.
